[57] ABSTRACT

[51] Int. Cl. A63d 15/10

A training aid-guide device for a pool or billiard cue is adapted to be easily held by the user by reason of a configuration featuring a generally rectangular elongate body having a thumb notch in one corner, a palm abutment in spaced opposition, a cue notch above the thumb notch and a generally flat bottom edge for supporting contact with a pool or billiard table.

PATENTED DEC 3 1974

3,851,876

FIG. 2

FIG. 3

TRAINING AID-GUIDE DEVICE FOR POOL CUE

The present invention relates broadly to games and, more specifically, to games employing a pool or billiard cue which is manually, axially stroked and thusly employed to move one ball or a plurality of balls about an elevated playing surface, usually a table; all of said games having objects and methods of competitive scoring peculiar to the particular game. The cue which is used to strike the balls has a butt end adapted to be grasped by the hand of the user, a generally tapered median region terminating in a cushion tip for transmitting the force of the axial stroke to the ball. The cushion tip is usually felted and powdered to avoid slippage, insure good contact and enable the skillful user to impart spin to the ball for purposes of intricate control of the path before and after striking an edge of the table or another ball. The variation in skill and control of the ball movement by the cue determines the achievement of the objects and outcome of the competition.

In employing the pool cue, the right-handed user holds the butt end in his right hand and manipulates the fingers and associated parts of the left hand opposite to form an intricate guide for the tapered region of the cue so that it can be axially moved to and fro to guide the pool cue in the desired stroke path. Many people simply create a V notch between a thumb and the adjacent region of the hand at the butt end of the forefinger. Others manipulate their index finger into an inverted U which, together with associated parts of the middle finger and with appropriate support of the other fingers, creates a suitable guide, permitting skillful stroking of the pool cue and achievement of the desired movement of the ball and/or balls in keeping with the objects of the game and the exigencies of the lay of the table at the time.

People, particularly children and females, introduced to the game of pool have difficulty with this part of the game; namely, the manual dexterity necessary to contort the fingers and hand into a suitable guide support for the axially reciprocating cue. This can result in early disgust and failure to progress in the appreciation of the enjoyment of the various games of this type. Lack of skill in this area can also lead to damage, not only to the pool cue but to the table top since a miscue can cause the cushion tip of the cue to rip the covering of the table which is usually of fairly high-grade felt and also involving fairly expensive labor costs.

With the foregoing general introduction, it is an object of the present invention to provide a device in the nature of a training aid or guide which can be easily employed by the beginner of whatever age and so employed permit this individual to control the axial movement of the pool cue in an advantageous and desirable manner.

It is an additional object of the present invention to provide such a device which combines several features of structure which allow it to be very easily and naturally held by either hand of the user, depending on whether he be right-handed or left-handed or even if he be manually handicapped to some degree.

It is yet another object of the present invention to provide such a device which is extremely simple in design and is accordingly quite inexpensive and readily manufactured and available to the user at low cost.

It is still another object of the present invention to provide such a device which is so contoured and de-

signed as to allow a gradual transition from initial holding to a more advanced state of holding which more closely approximates the hand position of the experienced pool or billiard player who does not employ such training aid or guide member.

It is also an object of the present invention to provide such a device whose design and configuration is of such simplicity that it can be fabricated of a variety of materials of construction ranging from wood to metal to plastic; with the latter probably being preferred since it would permit multi-cavity molding production of the devices of the present invention at extremely low cost.

The within objects and, as well, other objects of the present invention will become apparent to those skilled in the art from the following detailed description taken in conjunction with the annexed sheet of drawings on which there is presented, for purpose of illustration only, a single embodiment of the present invention.

IN THE DRAWINGS:

FIG. 1 is a three-quarter perspective view from above showing the training aid-guide device of the present invention gripped in the hand of the user; the hand being shown in dotted outline;

FIG. 2 is a somewhat similar view to FIG. 1 but from side elevation in order to show the relationship of the hand and its parts with the table; and

FIG. 3 is a view similar to FIG. 2 but showing the positioning of the hand in a more advanced stage of usage of the training aid-guide device of the present invention.

Considered most simply, the device of the present invention is a relatively flat or planar body of generally elongate configuration which features, in one corner, a thumb notch and, in an upper generally opposed edge, a slightly tapered region terminating in an abutment; the latter features cooperating with the thumb to provide a natural gripping of the tapered region and the abutment with that region on the palm just rearwardly of the fingers; the device featuring additionally, just above the thumb notch, a concave notch for the pool cue and a generally flat bottom edge for smooth supporting contact with the pool table.

Referring now more specifically to the drawings, the reference numeral 10 identifies the surface of the pool table, while the reference numeral 12 identifies the training aid-guide device of the present invention. As can be seen, the guide member or training aid 12 is relatively flat and rather elongate, having, in a lower corner, an arcuate cutout serving as a convenient notch 14 for a thumb T. The thumb notch curves downwardly to intersect the bottom edge 16 which is flat and proceeds linearly to the opposite end of the device 12 wherein there is conveniently provided a through hole 17 for attachment of a leather thong or the like for attachment to the wrist or for whatever suits the whim of the user. Other than the through hole 17, the far end of the guide member is relatively nonfunctional excepting that it is the starting point of the upper edge 18 which extends divergently to the right with respect to the bottom edge 16 and finally juts abruptly upwardly at 19 to form the abutment at 20. The abutment crowns at 21. The edge of the device then proceeds further to the right to define a concave cue guide notch 24 which, as can be seen, is situated just above the thumb notch. The cue stick is shown in dotted outline and identified by refer-

ence legend Q. The thumb notch terminates in an abutment or crown 26 which confines or limits the lateral movement of the cue to the notch. From the crown 26, the edge proceeds vertically as at 27 to the thumb notch 14.

Now in usage, it is observed that (1) the thumb notch 14, (2) the gradual converging taper 18 of the upper edge and (3) the abutment 20 cooperate to allow the hand H (shown in dotted outline) to very easily, and without stress or strain, grip in a very natural way the training aid or guide member 12 in the manner illustrated in FIG. 1 and, for that matter, in FIG. 2. The fingers of the hand are not necessary to hold the device in what appears to be defiance of the law of gravity. The surfaces 18 and 19 and abutment 20 can be seen to oppose the thumb notch 14 such that the slight gripping action of the thumb compresses the device naturally, without appreciable effort and without requiring the assistance of the fingers which can extend naturally outwardly and resting on the surface of the table 10 as illustrated in FIG. 2. In this position, the notch 24 will be in a very natural position with respect to the other parts of the hand and will very closely approximate the position of the cue with respect to the hand as practiced by the experienced pool or billiard player who is not using the guide member of the present invention but rather is employing or manipulating his fingers into a guide for the cue. Also cooperating with the above features is provision for the flat bottom edge 16 which, resting on the pool table, provides through the contour of the edge 18 a firm support to the hand and particularly the knuckle region in a gradually downward sloping relationship as illustrated in FIG. 1. Here again, these cooperating features allow the left hand, as illustrated in these figures, to be in a very relaxed position and yet at the same time allowing the user to have under his control a firm, guide notch for the pool cue. The nervousness and uncertainty of the neophyte is not transmitted through the hands to the cue as might be otherwise evidenced by a visibly shaking support. Rather, the bottom edge 16, the upper edge 18 and the natural finger position against the table, coupled with the secure feeling provided by the thumb notch, allow the person employing the guide member or training aid to have on the table a firm and stable guide for his pool or billiard cue.

As the player's confidence increases due to improved skill and his familiarity, he may and usually will progress to holding the device of the present invention in the manner illustrated in FIG. 3. The only difference, between the hand and finger position as shown in FIG. 3 and that as shown in FIG. 2, is that the fingers are wrapped around the device and the bottom edge 16 will be resting on the fingers, usually proximate the first

joint inward from the finger tips. Considering this positioning, it is easy to see that it is a natural evolution for the user to gradually move the forefinger closer and closer to the cue notch in somewhat of a covering or bridge relationship. Once this stage has been achieved, it is again a natural and easy next evolutionary step for the user to discard the guide member entirely and go to relying upon his fingers alone. Accordingly, the device of the present invention is seen as uniquely designed to not only provide an aid of utility to the beginner but is such as to encourage and allow the user to advance and progress in a natural manner to a finger and hand positioning which is very close to the positioning of the hand and fingers as configurated by the skilled or experienced pool or billiard player.

Actual guide members which have been built in accordance with the foregoing principles measure about 3 to 6 inches long by from $\frac{1}{8}$ to $\frac{1}{2}$ inches thick. The slope of the upper edge 18 with respect to the bottom edge 16 measures approximately from 8° to 12° .

It will be appreciated that variations and modifications may be made and embodied in devices like the one disclosed and it is the intent to include all such within the scope of the present invention unless such would violate the language of the appended claims.

I claim:

1. A hand-held guide device for pool or billiard cues, said device comprising a principal body of sheet material having a generally rectangular elongate configuration and adapted to be held by an average hand,
  - a. said body having an upper notch in one corner receptive of a pool cue and serving as a guide or support for the cue in its normal axial movement in use as controlled by the user,
  - b. said body including a cut out thumb notch in a corner next adjacent said one corner and beneath the upper cue notch, accommodating the thumb of the user in a natural holding or gripping of the device, said notch being contoured and located to receive lateral and upward thumb pressure, and
  - c. said body including an upper edge adapted for contact with the palm of the hand of the user when the user's thumb is contacting said notch and said upper edge in contact with said palm providing oppositional pressure of said palm meeting generally upward and lateral thumb pressure applied on the thumb notch by the user, whereby hand holding of the device is facilitated.

2. The invention as claimed in claim 1, wherein said upper edge includes an abutment for the contact of the palm near the root of the index finger of the user, accentuating the opposition of the palm to the thumb pressure.
